DESIGN FOR A TRANSPORTATION TICKET BLANK

Joseph Mehlman, Los Angeles, Calif.

Application October 29, 1935, Serial No. 59,263

Term of patent 14 years

To all whom it may concern:

Be it known that I, Joseph Mehlman, a citizen of the United States, residing at Los Angeles, and State of California, have invented a new, original, and ornamental Design for Transportation Ticket Blanks, of which the following is a specification, reference being had to the accompanying drawing, forming part thereof.

The figure is a fragmentary plan view of a transportation ticket blank, showing my new design.

I claim:

The ornamental design for a transportation ticket blank, as shown.

JOSEPH MEHLMAN.
